UNITED STATES PATENT OFFICE

97,741

DESIGN FOR A FLUID TREATING VESSEL FOR OIL REFINERY

Ralph M. Parsons, Mount Vernon, Ohio, assignor
to The Ralph M. Parsons Company, Mount
Vernon, Ohio, a corporation of Delaware

Application March 2, 1935, Serial No. 55,690

Term of patent 14 years

To all whom it may concern:

Be it known that I, Ralph M. Parsons, a citizen of the United States, residing at Mt. Vernon, in the county of Knox and State of Ohio, have invented a new, original, and ornamental Design for a Fluid Treating Vessel for Oil Refinery, of which the following is a specification, reference being had to the accompanying drawing, forming part thereof, in which

Fig. 1 is an elevational view of a fluid treating vessel for oil refinery showing my new design, and
Fig. 2 is a top plan view thereof.

A characteristic of my design resides in a support for a cylindrical vessel comprising supporting legs engaging at their upper ends projecting ears, each ear having a vertical part with straight sides and rounded front, and horizontal beads extending around both the top and the bottom of said part.

I claim:

The ornamental design for a fluid treating vessel for oil refinery, as shown and described.

RALPH M. PARSONS.
